United States Patent

Des. 241,773

Patented Oct. 5, 1976

241,773

VIEWER HOUSING

Marvin E. Lebow, 3431 E. 62nd Place,
Tulsa, Okla. 74136

Filed May 9, 1975, Ser. No. 576,885

Term of patent 14 years

Int. Cl. D16—02

U.S. Cl. D16—14

Fig. 1

Fig. 2

Fig. 3

Fig. 4

Fig. 5

Fig. 6

FIG. 1 is a top plan view of a viewer housing showing my design;

FIG. 2 is a bottom plan view;

FIG. 3 is a front elevational view;

FIG. 4 is a side elevational view;

FIG. 5 is a rear elevational view; and FIG. 6 is a side elevational view opposite that shown in FIG. 4.

I claim:

The ornamental design for a viewer housing, substantially as shown and described.
